[57] CLAIM

The ornamental design for a sleepwear hanger, substantially as shown and described.

DESCRIPTION

FIG. 1 is a reduced front perspective view of a sleepwear hanger showing our new design;

FIG. 2 is a front elevational view thereof;

FIG. 3 is a top plan view thereof;

FIG. 4 is a bottom plan view thereof;

FIG. 5 is a side elevational view taken from the right of FIG. 2;

FIG. 6 is a side elevational view taken from the left of FIG. 2.

The rear face of the hanger is not ornamented.

Fig. 6.

Fig. 5.
